UNITED STATES PATENT OFFICE.

JOHN ROBERT SPEAR AND JAMES MILTON BEATTIE, OF WINNIPEG, MANITOBA,
CANADA.

GROUND-STRIP FASTENER.

1,145,933.

Specification of Letters Patent.

Patented July 13, 1915.

Application filed April 6, 1914. Serial No. 829,942.

To all whom it may concern:

Be it known that we, JOHN ROBERT SPEAR and JAMES MILTON BEATTIE, both of the city of Winnipeg, in the Province of 5 Manitoba, Canada, have invented certain new and useful Improvements in Ground Strip Fasteners, of which the following is the specification.

The invention relates to improvements in 10 ground strip fasteners and the object of the invention is to provide an inexpensive, efficient and durable fastener which can be placed at any point in a wall to effect the fastening of the ground strip to the wall, it being understood that the invention is especially adaptable in building constructions 15 wherein it is required to effect the fastening of a ground strip to a plaster, tile or such like fire proof wall or partition without being restricted by the location of the joints between blocks as occurs in the present practice.

With the above object in view the invention consists essentially in a perforated plate 20 fitted with an out-turned pair of opposing flanges and an adjoining pair of outstanding fastening jaws, the parts being arranged and constructed as hereinafter more particularly described and later pointed out 25 in the appended claim.

Figure 1 represents a perspective view of the device as applied in a wall. Fig. 2 represents a vertical sectional view through the wall, fastener, ground strip and facing 30 strip, the section being taken in the plane denoted by the line X—X' Fig. 1.

In the drawing like characters of reference indicate corresponding parts in each figure.

40 1 represents a wall or partition formed as is common practice from similar fire-proof blocks 2 built up one on the other and having mortar, cement or other similar bonding material 3 appearing between the successive courses.

45 4 represents our fastener which is in the form of a substantially rectangular sheet metal plate having the body portion thereof suitably perforated as indicated at 5.

50 50. The material of the plate is cut and bent to provide a pair of outstanding parallel

flanges 6 and 7 and also to provide an adjoining pair of outstanding more or less V-shaped jaws or fastening members 8 and 9 the members having their extremities turned 55 inwardly, that is toward each other to present piercing points 10.

In using our invention to fasten a ground strip to a wall or partition a number of 60 the fasteners are used, each fastener being provisionally fastened to the wall by driving in corner nails such as those 11 if the nature of the wall permits or by applying composition such as plaster of Paris to bond 65 it to the wall in instances where it is impossible to drive a nail. The wooden ground strip 12 is then placed in position on the wall being received between the flanges 6 and 7 of the various fasteners, the flanges holding the ground strip in place until such 70 time that the builder can drive the piercing points 10 of the various jaws into the ground strip. When the jaws have been driven in, the wall is plastered in the usual way, the plaster 13 being applied over the fastenings 75 and thereby securing the fastenings permanently and finally to the wall. It is to be noticed that the forward face of the ground strip is exposed through the plaster so that the facing strip 14 can be readily nailed to 80 the ground strip.

We might remark that in ordinary practice it is customary to insert the ground strip between the blocks of the wall it being fastened in the bonding material between 85 the blocks. This construction however limits the position of the ground strip as it can only appear at the bond between the blocks. With our invention it is wholly immaterial where the ground strips are located as they 90 can be placed at any point on the wall by simply locating and provisionally fastening the fasteners in any desired position on the wall, then mounting and fastening the ground strips to the fasteners and lastly 95 plastering the wall to finally hold the fasteners.

What we claim as our invention is;

A ground strip fastener comprising a flat 100 perforated plate fitted with a pair of outstanding opposing jaws having teeth adapted to enter a ground strip and prevent lon-

gitudinal or transverse movement thereof, and an adjoining alined pair of opposing outstanding flanges, adapted to prevent vertical movement of said ground strip, as and for the purpose specified, said jaws and flanges being stamped from the body of the plates whereby further perforations are provided.

Signed at Winnipeg this 12th day of February 1914.

JOHN ROBERT SPEAR.
JAMES MILTON BEATTIE.

In the presence of—
G. S. ROXBURGH,
S. SILVERT.
